DESIGN FOR A DRESS

Ben Machanoff, New York, N. Y.

Application August 30, 1938, Serial No. 79,631

Term of patent 3½ years

To all whom it may concern:

Be it known that I, Ben Machanoff, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

The characteristic feature of my design resides in the combination on the dress disclosed of the particular bead trim on the neckline and bust portions, as shown.

I claim:

The ornamental design for a dress, substantially as shown, and described.

BEN MACHANOFF.
